United States Patent Office.

RICHARD ORFORD, OF DOWAGIAC, MICHIGAN.

Letters Patent No. 96,141, dated October 26, 1869; antedated October 12, 1869.

IMPROVED SACCHARINE EVAPORATOR.

The Schedule referred to in these Letters Patent and making part of the same.

To all whom it may concern:

Be it known that I, RICHARD ORFORD, of Dowagiac, Michigan, have invented a new and improved Method of Constructing Furnaces, and of Arranging the Flues and Dampers of Saccharine Evaporators; and I do hereby declare that the following is a full, clear, and exact description of the construction and operation of the same, reference being had to the annexed drawings, making a part of this specification, in which—

Figure 1 is a side view, and

Figure 2 is a detached section, showing the arrangement of the flues and dampers, and method of lining the furnace.

The nature of my invention consists in so arranging the flues and dampers as to avoid the danger of burning the sirup or sugar, to a great extent; and in fastening the brick or mason-work of furnaces without using mortar; and, also, in providing adjustable legs, for the purpose of levelling the evaporator.

To enable others skilled in the arts to make and use my invention, I will proceed to describe its construction and operation.

I construct the pan A in any of the known forms.

Where the saccharine is siruped down, in the rear end of the pan, the rear end of the furnace B is provided with the flues C D and dampers E F.

The dampers are connected by means of the bar G, causing a simultaneous action of the dampers E F as the bar G is moved, by which means both ends of the flue C are closed at once, thus preventing the heat from passing under the rear of the pan A, which it could do if the rear end of the flue C were not closed, and

more effectually excludes the heat than could be done with a single damper.

H is a thin bar of iron, covering the joints in the brick or stone lining to the furnace B, fastened by means of bolts or rivets j j, passing through between the brick k k, and through the sides of the furnace B, for the purpose of holding the brick or mason-work of the furnace more securely than could be done by mortar. The bars H may be replaced, when burned out, by new ones.

S are brackets, fastened to the sides of the furnace, with projections at the top to support the pan.

a a are legs, provided with broad feet, attached with swivel-joints, and screw into projections on the brackets S, and may be conveniently lengthened or shortened, in order to level the evaporator.

X is a gripe, for the purpose of supporting the centre of the furnace, and for holding the pan from springing up.

Having thus described my invention,

What I claim as new, and desire to secure by Letters Patent, is—

The combination and arrangement of the furnace B, with its bars H, rivets j, dampers E and F, brackets S, and bar G, with the pan A of a saccharine evaporator.

In testimony that I claim the foregoing, I have hereunto set my hand, this 15th day of October, 1868.

RICHARD ORFORD.
